US0D1067913S

(12) **United States Design Patent** (10) **Patent No.:** **US D1,067,913 S**
(45) **Date of Patent:** **** Mar. 25, 2025**

(54) **REMOTE CONTROLLER**

(71) Applicant: **Samsung Display Co., Ltd.**, Yongin-si (KR)

(72) Inventors: **Jyeon Kim**, Yongin-si (KR); **Hyun Joo Lee**, Yongin-si (KR); **Hyun Gu Kim**, Yongin-si (KR); **Sungsu Park**, Yongin-si (KR)

(73) Assignee: **Samsung Display Co., Ltd.**, Yongin-si (KR)

(**) Term: **15 Years**

(21) Appl. No.: **29/867,258**

(22) Filed: **Oct. 17, 2022**

(30) **Foreign Application Priority Data**

Apr. 18, 2022 (KR) 30-2022-0015205

(51) **LOC (15) Cl.** **14-02**

(52) **U.S. Cl.**

USPC **D14/388**

(57) **CLAIM**

The ornamental design for a remote controller, as shown and described.

DESCRIPTION

FIG. 1 is a perspective view of the remote controller in a folded configuration;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the remote controller in an unfolded configuration;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof; and,

FIG. 15 is a perspective view of the remote controller in a partially unfolded configuration.

The broken lines showing portions of the remote controller are for the purpose of illustrating unclaimed portions of the remote controller, and form no part of the claimed design.

1 Claim, 15 Drawing Sheets
